CLAIM

The ornamental design for a novelty figure made of
rope, as shown and described.

DESCRIPTION

FIG. 1 is a front elevational view of a novelty figurine
showing my new design, the base shown in a broken
lines for illustrative purposes only;

FIG. 2 is a side elevational view thereof taken from the
right of FIG. 1, the opposite side being a mirror image
thereof;

FIG. 3 is a back elevational view thereof;

FIG. 4 is a bottom plan view thereof;

FIG. 5 is a front elevational view of a second embodiment
of FIG. 1, the difference residing in the placement
of the eyes;

FIG. 6 is a front elevational view of a third embodiment
of FIG. 1, the difference residing in the configuration of
the head and eyes.
